(57) **CLAIM**

The ornamental design for a dispensing container, as shown and described.

DESCRIPTION

FIG. 1 is a perspective view of a dispensing container showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the dispensing container showing our new design in a state in which the cap is separated therefrom;

FIG. 9 is a perspective view of the dispensing container showing our new design in a state in which the cap is combined with the dispensing container; and,

FIG. 10 is a cross-sectional view according to the line A-A of FIG. 3 showing the inside of the cap in a state in which the cap is combined with the dispensing container.

The broken lines in FIGS. 8 to 10 are for illustrative purpose only and form no part of the claimed design.
